UNITED STATES PATENT OFFICE

162,296

PRESSURE SPRAY DEVICE

Thomas T. Graham, Houston, Tex., assignor of
one-half to Ocie P. Alexander, Houston, Tex.

Application September 29, 1949, Serial No. 5,213

Term of patent 14 years

(Cl. D62—2)

To all whom it may concern:

Be it known that I, Thomas T. Graham, a citizen of the United States, residing at Houston, in the county of Harris, State of Texas, have invented a new, original, and ornamental Design for Pressure Spray Device, of which the following is a specification, reference being had to the accompanying drawing, forming part thereof.

Figure 1 is a side elevation of a pressure spray device, showing my new design,

Figure 2 is a plan view, and

Figure 3 is a bottom view.

I claim:

The ornamental design for a pressure spray device, as shown.

THOMAS T. GRAHAM.
